UNITED STATES PATENT OFFICE.

JOHN WORSLEY, OF PROVIDENCE, RHODE ISLAND.

IMPROVED BRAKEMAN'S LIFE-PRESERVER FOR RAILROAD-CARS.

Specification forming part of Letters Patent No. 44,134, dated September 6, 1864.

To all whom it may concern:

Be it known that I, JOHN WORSLEY, of Providence, in the State of Rhode Island, have invented a new and useful Life-Protector for the Brakemen of Railroad Cars, and I do hereby declare that the following is a full, clear, and exact description of my invention, reference being had to the accompanying drawings, in which—

Figure 1 represents a view, in perspective, of the principal portions of a railroad freight-car with my life-protector applied thereto and in use. Fig. 2 represents a side view of the principal portions of a car with the life-protector applied thereto, and Fig. 3 represents an end view of the same.

Railroad freight-cars for the transmission of merchandise, grain, and live-stock consist mainly of a box-body mounted upon a platform and of the running gear. The brakes of such cars are of necessity beneath the box-body, and, as the box-body prevents the passage of the brakeman from car to car along the platform of a train of such cars, the brake-stands are generally extended up to brake-wheels at or near the tops of the cars, and the brakeman is compelled to pass along the tops or roofs of the bodies when passing from car to car to apply the brakes. This passage along the tops of the cars is perilous at all times on account of the rocking of the cars and the rapid motion, but it becomes especially so during storms of rain and violent winds, and in winter, when the roofs of the cars are frequently coated with snow and ice, which render the footing uncertain. The peril is so great that every year many brakemen are crippled for life by being thrown from freight-trains, or by slipping off, and a number are killed. The danger to the brakemen is not all that is to be feared, for it frequently happens that the train cannot be stopped from the loss of the brakemen, who have been thrown from the cars at night or during storms of sleet and snow without the knowledge of the engineer, and in such cases severe accidents have occurred from the train running into other trains or running off the track.

The object of my invention is to materially lessen, if not wholly prevent, the danger to the brakemen of railroad freight-cars; and it consists of the combination of the box-body of a railroad car with what I denominate a

"brakeman's life-protector" upon its roof, which protector consists of a traverse-rod and its appurtenances, (substantially as hereinafter set forth,) by whose assistance the brakeman can pass along the roof of the car from end to end without material danger.

The accompanying drawings represent my invention in the best form in which I have thus far embodied it. In the drawings, the freight car represented is of the ordinary construction, with a platform, A, two trucks, B B, and a box-body, C, mounted on the platform. The brakes may be connected in any of the usual modes with the running-gear, and as such modes are well known it is not necessary to describe and represent them in detail, the brake-standard *d* being arranged at one end of the box-body and being extended upward until its upper end, which is provided with a brake-wheel, E, is a short distance above the roof of the car. The car thus represented is provided with two of my life-protectors, one at each side of the roof M. Each is composed of a traverse-rod, *m*, supported and secured to the car-body at its ends by standards *k k*. The traverse-rod must of necessity be but little above the roof of the car, because it must not be in the way when the car is passing beneath bridges or through tunnels. It may be constructed of a bar of iron, or it may be formed of wire rope, or of chain, secured at the ends to standards, which connect it with the car-body. Each of the traverse-rods is fitted with a traverser or ring, *e*, which can traverse along it, and to each traverser a hand-ring, *a*, is connected by a short chain, *n*, so that a brakeman passing along the roof of the car from end to end can seize the traverse-rod or the hand-ring of the traverser and thereby connect himself with the car and hold on while he is moving along its roof. In order that he may find the hand-ring of the traverser with facility, each standard *k* is forked at its upper end to form a fork upon one of the horns *i*, on which the hand-ring may be hung when the brakeman leaves one car and passes to the roof of the next one. In order that he may be able to place the hand-ring in the fork of the standard with facility and certainty at night, one of the horns, *i*, is made lower than the other horn, *s*, of the standard, so that the ring passed over the lower will strike the higher, and thus be guided

into the fork. I have deemed it best to arrange one of my life-preservers at each side of the roof of the car; but, if preferred, one may be arranged at the center of the car-roof, or at one side of the foot-board *t*, which extends along the middle of the roof. It is desirable that there should be no impediment between the standards at the ends of the traverse-rod to prevent traversing along it; but, on the other hand, it is desirable that the traverse-rod should be sustained between its ends when a great strain is put upon it, such as might occur from the slipping of the brakeman. In order to obtain such support without materially affecting the freedom of traversing, I make use of standards *f*, which are secured to the car-body roof at short distances from the direct line of the traverse-rod and at one or both its sides, as deemed expedient, so that when the traverse-rod is deflected out of its direct line by great strain it will come in contact with one or more of such intermediate sustaining-standards, and be thereby sustained, while, on the other hand, they, being

situated at a short distance from the traverse-rod when it is not deflected, will permit traversing upon it.

What I claim as my invention, and desire to secure by Letters Patent, is—

1. The combination of the before-described brakeman's life-protector with the car-body of a railroad-car, substantially as set forth.
2. The end standard constructed with a fork to hold the hand-ring of the traversing-chain in a position where it may be found with facility, substantially as set forth.
3. The combination of the brakeman's life-protector with intermediate sustaining-standards projecting above the roof of the car-body between the ends of the rod, substantially as set forth.

In testimony whereof I have hereunto set my hand.

JOHN WORSLEY.
